(74) Attorney, Agent, or Firm — ZANIP

(57) **CLAIM**

The ornamental design for an airbed, as shown and described.

DESCRIPTION

FIG. 1 is a perspective view of an airbed, showing my new design;

FIG. 2 is an additional perspective view thereof;

FIG. 3 is an additional perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.
